(57) CLAIM

(51) LOC (14) Cl. 21-01

The ornamental design for a toy dressing table, as shown and described.

(52) U.S. Cl.

DESCRIPTION

USPC D21/522

FIG. 1 is a perspective view of portions of the front, top, and left sides of a toy dressing table showing my new design; FIG. 2 is a perspective view of portions of the rear, top, right sides thereof;

FIG. 3 is a front view thereof;

FIG. 4 is a rear view thereof;

FIG. 5 is a top plan view thereof;

FIG. 6 is a right side view thereof; and,

FIG. 7 is a left side view thereof.

The broken lines shown are included for the purpose of illustrating portions of the article which form no part of the claimed design.
